(57) **CLAIM**

The ornamental design for CCFL connector assembly, as shown and described.

DESCRIPTION

FIG. 1 is a perspective view of CCFL connector assembly showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view showing the design of CCFL connector assembly in a usage condition showing the design deployed in a multiple configuration.

The broken lines in the Figures show unclaimed detail only and form no part of the claimed design.
